US00D866488S

(12) **United States Design Patent** (10) Patent No.: **US D866,488 S**
(45) Date of Patent: ** *Nov. 12, 2019

(54) **KEYPAD**

(71) Applicant: **Lutron Technology Company LLC**,
Coopersburg, PA (US)
(72) Inventors: **Alexander Wade Gage**, Havertown, PA
(US); **Elliot G. Jacoby**, Glenside, PA
(US); **Jason C. Killo**, Emmaus, PA
(US); **Brad Michael Kreschollek**,
Bethlehem, PA (US); **Daniel Curtis**
Raneri, Bethlehem, PA (US)

(73) Assignee: **Lutron Technology Company LLC**,
Coopersburg, PA (US)

(*) Notice: This patent is subject to a terminal disclaimer.

(**) Term: **15 Years**

(21) Appl. No.: **29/646,342**

(22) Filed: **May 3, 2018**

Related U.S. Application Data

(63) Continuation of application No. 29/590,775, filed on
Jan. 13, 2017, now Pat. No. 820,796, which is a
continuation of application No. 29/536,802, filed on
Aug. 19, 2015, now Pat. No. Des. 780,133.

(57) **CLAIM**

The ornamental design for a keypad, as shown and
described.

DESCRIPTION

FIG. 1 is a front perspective view of a keypad showing our
new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The dashed broken lines represent structure or features
which form no part of the claimed design; the broken lines
themselves form no part of the claimed design.

1 Claim, 4 Drawing Sheets
